(57) **CLAIM**

The ornamental design for a seat pan adjustment wing, as shown and described.

DESCRIPTION

FIG. 1 is an isometric view of a seat pan adjustment wing according to the present invention;

FIG. 2 is a top view of the seat pan adjustment wing of FIG. 1;

FIG. 3 is a bottom view of the seat pan adjustment wing thereof;

FIG. 4 is a side elevation view of the seat pan adjustment wing thereof;

FIG. 5 is an opposite side view of the seat pan adjustment wing thereof;

FIG. 6 is an end view of the seat pan adjustment wing thereof;

FIG. 7 is an opposite end view of the seat pan adjustment wing thereof; and,

FIG. 8 is an alternate isometric view of the seat pan adjustment wing thereof.

The broken line portion of the figures is included to show unclaimed subject matter only and forms no part of the claimed designs.
